L. Bradford Standish
his ATTORNEY

UNITED STATES PATENT OFFICE.

RALPH ERNEST JONES, OF CAMP GAILLARD, CANAL ZONE.

VARIABLE-PRESSURE REGULATOR.

Application filed May 28, 1923. Serial No. 641,975.

To all whom it may concern:

Be it known that I, RALPH ERNEST JONES, a citizen of the United States, residing at Camp Gaillard, in the Canal Zone, have 5 invented certain new and useful Improvements in Variable-Pressure Regulators, of which the following is a specification:

This invention relates to a variable pressure regulator, that is to a device which may 10 be adjusted at will and will thereafter automatically regulate and determine the pressure of fluid passing therethrough.

An object of the invention is to provide a simple, practical and efficient device by 15 which the pressure to be delivered may be easily and accurately determined or by which the pressure delivered may be altered as frequently as may be desired.

Other objects and aims of the invention, 20 more or less specific than those referred to above, will be in part obvious and in part pointed out in the course of the following description of the elements, combinations, arrangements of parts and applications of 25 principles, constituting the invention, and the scope of protection contemplated will be indicated in the appended claims.

In the accompanying drawings which are to be taken as a part of this specification, and 30 in which I have shown merely a preferred form of embodiment of the invention:

Figure 1 is a vertical central sectional view through the regulator constructed in accordance with this invention.

Figure 2 is a transverse sectional view taken substantially upon the plane of line 35 II—II of Fig. 1, and

Figure 3 is a similar sectional view taken upon the plane of line III—III of Fig. 1.

Referring to the drawings for describing in detail the structure therein illustrated, the reference character L indicates the body of the regulator. This is provided with a main chamber 1 extending longitudinally thereof, being closed at its lower end as at 2, and an auxiliary chamber 3 preferably parallel with the first chamber but of smaller area.

Within the chamber, or cylinder, 1, is arranged a piston 4 preferably provided with 50 suitable packing rings or the like, as intended to prevent the passage of any fluid upwardly from the space beneath the piston.

To the upper side of the piston is connected a piston rod 6 which continues upwardly along the axial line of the chamber 55 and carries at its upper end a head 7. This

head is intended to be freely rotatable relative to said rod, and for this purpose the drawing illustrates the rod to be provided with a reduced extension 8 upon which the 60 head is mounted and which provides a shoulder 9 for preventing movement of the head in one direction along the rod, movement in the opposite direction being prevented by a retaining nut or other like 65 member 10.

Arranged within the chamber and preferably surrounding the piston rod is a compression spring 11 adapted for urging the piston and the parts connected therewith 70 downwardly. The lower end of this spring engages the upper surface of the piston. The upper end of the spring may press against any part fixed to the body, but for convenience it is shown to rest against a perforated disc which is fixed within the chamber and through which the piston rod, loosely 75 passes.

Fitted into the upper end of the chamber is a rotatable sleeve G, and within this is a second and independently rotatable sleeve H. The sleeve G has a straight longitudinally extending slot 12 provided therein while the sleeve H has a relatively inclined slot as 13 formed longitudinally thereof. 80 The swivel head 7 is arranged within the sleeve H and is provided with a radially extending pin 14 which extends through the slot 13 and into the slot 12.

By this arrangement it will be apparent 90 that any movement of the piston either upwardly or downwardly relative to the sleeves will cause the sleeve H to rotate relative to the sleeve G.

The sleeve G is provided with an operating handle 15 which projects outwardly through an opening 16 of the body by which said sleeve may be manually, or otherwise, rotated into any desired position.

It may be here noted that the sleeve G will 100 be held in any position to which it may be moved by handle 15 either by frictional engagement of itself with the walls of the chamber or by a suitable spring gripping device such as is indicated by the reference 105 character 17. Also that suitable graduation marks may be provided associated with the handle and properly identified for visually determining the extent of movement necessary for said handle to produce any desired 110 pressure.

The upper end of sleeve H is shaped to

provide a simple plug valve as 18 which fits into a conical seat 19 provided to receive it in the upper end of the chamber. Any appropriate means may be provided for resiliently urging this valve to a proper position against said seat but for convenience the drawing illustrates a simple disc spring 20 resting upon the upper surface of said valve and being centrally engaged by an adjustable set screw 21 which is carried by a cover plate 22 of the body.

A supply passage 23, adapted for connection to any suitable source of fluid pressure is provided through the wall of the body 15 and communicates with the seat 19.

Also communicating with the seat 19, preferably at a point just below the passage or port 23 is a second passage 24 which leads into the upper end of the auxiliary chamber 3.

From this auxiliary chamber leads a discharge pipe 25 through which fluid at regulated pressure is to be discharged.

A suitable passage 26 communicates between the lower ends of the main and auxiliary chambers.

At another point in the seat 19 is a relief port or passage 27 communicating with the atmosphere.

Within the valve 18 is provided a suitable passage 28 for communicating at proper times with ports 23, 24 and 27.

The operation of the mechanism may now be understood as follows: Air, or other fluid pressure entering through port 23 will traverse the passage 28 of valve 18 and flow into the auxiliary chamber whence it will pass outwardly through the pipe 25, meanwhile, however, exerting its pressure, through passage 26, against the under surface of the piston so that the position of the piston will vary with any variation in the pressure entering the device. This movement of the piston will rotate the valve 18 either forwardly or backwardly as the case may be, that is according to whether the piston moves upwardly or downwardly, and will thereby automatically regulate the size of free opening between the port 23 and passage 28. A substantially uniform pressure is thus always delivered through pipe 25. It will be understood in this connection that upward movement of the piston will bring a solid wall surface as 29 of the valve across the port 23 and that the amount of free opening from said port will be determined by the extent to which said wall surface 29 covers said port. A heavy pressure entering the device and exerting its force against the piston will rotate the valve and thereby close down the size of the port to that extent necessary only for allowing passage of fluid sufficient to produce just the desired pressure in pipe 25.

The operation as thus far described is

based upon the supposition that the sleeve G is stationary so that the slot 12 thereof provides a fixed vertical path of movement for the pin 14, and it is the purpose of the spring device 17 above described to hold said sleeve in this relatively fixed position.

If now however, it is desired to increase the amount of pressure delivered to pipe 25, the operator, by grasping the handle 15 merely moves said handle backwardly, see 75 the arrow 30 in Fig. 2, to the desired extent, as may be indicated by suitable indicating marks either on the member 17 or on the body L. This movement obviously will rotate not only the cylinder G but, through 80 the medium of the pin 14 will likewise rotate the sleeve H and the valve, and by so doing will place the surface 29 of the valve relatively further away from the port 23 so that the piston must be raised correspondingly higher before said surface 29 will cut down the size of free opening from said passage 23. To raise the piston the increased distance of course requires greater pressure, and this increased pressure obviously will 85 flow into pipe 25 and will be maintained substantially uniform at its increased standard as long as the handle 15 remains in its newly adjusted position.

If, on the other hand, a decreased pressure is desirable for pipe 25 the operator will move the handle forwardly, see arrow 30, Fig. 2, which will bring the surface 29 across the port 23 thus shutting off the supply. At the same time an extended portion as 31 of the passage 28 will move into position more or less uncovering the exhaust port 27, a further extension as 32 of said passage 28 meanwhile maintaining communication with the passage 24 so that pressure from the pipe 25 and the auxiliary cylinder, and from beneath the piston, may exhaust to the atmosphere. As the pressure beneath the piston decreases the piston will move downwardly and gradually shut off the exhaust 100 and begin again to open the port 23. Any increase in the pressure will raise the piston and again open the exhaust port. Thus the reduced pressure in pipe 25 will be maintained as long as the handle 15 is allowed to 105 stand.

And now it may be noted that by proper manipulation of the handle 15, either manually, or otherwise, the pressure delivered to pipe 25 may not only be altered as indicated but may be gradually increased or diminished at will, or as often, or as regularly, or to any extent desired between zero and maximum.

It will also be noted that the strength of 125 spring 11 is a controlling factor in determining the amount of pressure passed at any given position of the handle 15, and hence that controlling mechanisms of different capacities may be provided by merely select- 130

ing a proper strength of spring for producing the desired results.

While only a single pair of slots 12-13, and a single pin 14 is referred to hereinabove, it will be noted that the drawing shows two such groups arranged at diametrically opposite sides of the piston rod, thus balancing the mechanism and producing a smoother action.

10 As many changes could be made in this construction without departing from the scope of the invention as defined in the following claims, it is intended that all matter contained in the above description, or shown in the accompanying drawings, shall be interpreted as illustrative only and not in a limiting sense.

Having thus described my invention, what I claim as new and desire to secure by Letters Patent is:—

1. A fluid pressure regulator comprising a rotary valve rotatable to control the amount of fluid passing, a cylinder, a piston longitudinally movable in said cylinder arranged to be moved by the passed fluid, an inclined slot and pin connection between the piston and the valve whereby movement of the piston will rotate the valve, and a manual control element for said connection comprising means whereby a given amount of movement of the piston may have a selectively determined effect upon the valve.

2. A fluid pressure regulator comprising a rotary valve rotatable to control the amount of fluid passing, a cylinder, a piston longitudinally movable in said cylinder arranged to be moved by the passed fluid, a member having a slot therein extending longitudinally in the direction of movement of the piston, a part carried by the valve having a slot therein positioned adjacent to the first slot but being inclined relative thereto, and a part carried by the piston engaging within said two slots whereby movement of the piston will cause said part carried thereby to move longitudinally along said slots and thereby rotate the valve.

3. A fluid pressure regulator comprising a rotary valve rotatable to control the amount of fluid passing, a cylinder, a piston longitudinally movable in said cylinder arranged to be moved by the passed fluid, a member having a slot therein extending longitudinally in the direction of movement of the piston, a part carried by the valve having a slot therein positioned adjacent to the first slot but being inclined relative thereto, a part carried by the piston engaging within said two slots whereby movement of the piston will cause said part carried thereby to move longitudinally along said slots and thereby rotate the valve, and means whereby said first slotted member is adjustable to thereby determine the operation of the valve.

4. A fluid pressure regulator comprising a

rotary valve rotatable to control the amount of fluid passing, a cylinder, a piston longitudinally movable in said cylinder arranged to be moved by the passed fluid, the valve having its axis of rotation substantially coincident with the axial line of the cylinder, a sleeve extending from the valve toward the piston, a piston rod extending from the piston into said sleeve, the sleeve having an inclined slot provided therein, and a part 75 carried by the piston rod engaging within said slot to thereby rotate the sleeve and valve by movement of the piston.

5. A fluid pressure regulator comprising a rotary valve rotatable to control the amount of fluid passing, a cylinder, a piston longitudinally movable in said cylinder arranged to be moved by the passed fluid, the valve having its axis of rotation substantially coincident with the axial line of the cylinder, a sleeve extending from the valve toward the piston, a piston rod extending from the piston into said sleeve, a second sleeve exteriorly of the first sleeve and within which the first sleeve is freely rotatable, 90 said sleeves having mating slots therein, the slot of one sleeve extending in a direction inclined relative to the direction of the slot of the other sleeve, and a member carried by said piston rod extending into said mating slots whereby to rotate the first sleeve and valve by movement of the piston.

6. A fluid pressure regulator comprising a rotary valve rotatable to control the amount of fluid passing, a cylinder, a piston 100 longitudinally movable in said cylinder arranged to be moved by the passed fluid, the valve having its axis of rotation substantially coincident with the axial line of the cylinder, a sleeve extending from the valve 105 toward the piston, a piston rod extending from the piston into said sleeve, a second sleeve exteriorly of the first sleeve and within which the first sleeve is freely rotatable, said sleeves having mating slots therein, the 110 slot of one sleeve extending in a direction inclined relative to the direction of the slot of the other sleeve, a member carried by said piston rod extending into said mating slots whereby to rotate the first sleeve and valve 115 by movement of the piston, and means whereby said second sleeve is adjustably rotatably mounted to thereby regulate the movement of the valve.

7. A fluid pressure regulator comprising a rotary valve rotatable to control the amount of fluid passing, a cylinder, a piston longitudinally movable in said cylinder arranged to be moved by the passed fluid, the valve having its axis to rotation substantially coincident with the axial line of the cylinder, a sleeve extending from the valve toward the piston, a piston rod extending from the piston into the sleeve, the sleeve having a slot therein, a member carried by 120 125 130

the piston movable therewith adapted to traverse said slot, means to determine the path of movement of said piston carried member in a manner to produce rotation 5 of the valve upon movement of the piston, and means whereby said path determining means is adjustable to change the path at will.

8. A fluid pressure regulator comprising 10 a rotary valve rotatable to determine the amount of fluid passing, a cylinder, a piston longitudinally movable in the cylinder arranged to be moved by the passed fluid, the valve having its axis of rotation substantial- 15 ly coincident with the axial line of the cylinder, a sleeve extending from the valve toward the piston, a piston rod extending from the piston into the sleeve, a second sleeve exteriorly of the first sleeve and within 20 which the first sleeve is freely rotatable, said sleeves having mating slots therein, the slot of one sleeve extending in a direction inclined relative to the direction of the slot of the other sleeve, a member swiveled upon 25 the piston rod to move therewith but being rotatable relative to said rod, said swiveled member having a part projecting through said mating slots whereby to rotate the first sleeve and valve by movement of the piston, 30 and means whereby to rotatably adjust said two sleeves as a unit to thereby regulate the movement of the valve.

9. A fluid pressure regulator comprising a cylinder, a piston movable in the cylinder, 35 spring means to urge the piston in one direction, valve means for regulating the pressure of passing fluid effective upon the opposite side of the piston, connections between said piston and said valve means to 40 control the operation of said valve means by movement of the piston, said connections including a pair of rotatably mounted sleeves, one sleeve being positioned within the other and being freely rotatable relative 45 thereto, said sleeves having mating slots therethrough, and an extension part of the piston projecting through said mating slots, the slot of one sleeve being inclined relative to the slot of the other sleeve whereby 50 movement of said extension part along said slots will rotate the inner sleeve relative to

the outer sleeve, and means including said projecting part whereby said two sleeves are rotatably adjustably as a unit to thereby regulate the effect of the piston movement upon 55 the valve means.

10. In a fluid pressure regulator, a rotary valve through which the fluid must pass for delivery, a piston arranged to be moved by the passed fluid, a sleeve connected with 60 said valve to rotate therewith, and means connected with the piston extending into the sleeve having operative connection with the sleeve to cause rotation of the sleeve and consequent rotation of the valve upon move- 65 ment of the piston.

11. In a fluid pressure regulator, a rotary valve through which the fluid must pass for delivery, a piston arranged to be moved by the passed fluid, a sleeve connected with 70 said valve to rotate therewith, and means connected with the piston extending into the sleeve having operative connection with the sleeve to cause rotation of the sleeve and consequent rotation of the valve upon 75 movement of the piston, together with a manually operable member adapted to be selectively positioned to determine the effect of a given amount of movement of the piston upon the action of the valve. 80

12. A fluid pressure regulator comprising a rotatable valve member rotatable to control the amount of fluid passing, a cylinder, a piston member movable within said cylinder arranged to be moved 85 by the passed fluid, the valve member having its axis of rotation substantially coincident with the axial line of the cylinder, a sleeve extending co-axially from one of said mentioned members toward the other 90 mentioned member, a piston rod extending co-axially from said other mentioned member into said sleeve, and said sleeve and said piston rod having interengaging parts 95 whereby movement of the piston device will rotate the valve device.

In testimony whereof I affix my signature in the presence of two witnesses.

RALPH ERNEST JONES.
